UNITED STATES PATENT OFFICE.

LEVI PENTZ, OF CANTON, OHIO, ASSIGNOR OF TWO-THIRDS TO JOSEPH L. HIGLEY AND GEORGE N. YOHE, OF SAME PLACE.

BARREL-ELEVATOR.

SPECIFICATION forming part of Letters Patent No. 319,119, dated June 2, 1885.

Application filed February 16, 1885. (No model.)

To all whom it may concern:

Be it known that I, LEVI PENTZ, a citizen of the United States, residing at Canton, in the county of Stark and State of Ohio, have invented certain new and useful Improvements in Barrel-Elevators; and I do hereby declare that the following is a full, clear, and exact description of the same, reference being had to the annexed drawings, making a part of this specification, and to the letters and figures of reference marked thereon, in which—

Figure 1 is an isometrical view of the entire invention. Fig. 2 is a detached view of joint or hinge at *x*, Fig. 1, being shown partly in section. Fig. 3 is a detached view of joint or hinge-arm of the joint *x*, Fig. 1. Fig. 4 is a detached view of joint or hinge-arm of the joint *z*. Fig. 5 is a detached view of handle and skid for barrel-truck. Fig. 6 is a side elevation showing barrel-truck fully elevated and barrel dumped. Fig. 7 is a side elevation of barrel-truck, showing handle and skid attached. Fig. 8 is a side elevation showing the truck dumped at the bottom of elevator.

The present invention has relation to elevators designed to lower barrels or other heavy articles into cellars, or elevate said articles from cellars or into the upper stories of buildings; and its nature consists in the different parts and combination of parts hereinafter described, and particularly pointed out in the claims.

Similar letters of reference indicate corresponding parts in all the figures of the drawings.

In the accompanying drawings, *A* represents the track, which is composed of two parallel pieces of wood or iron, which constitute the track proper, said parallel pieces being held at the desired distance apart by suitable cross pieces or ties, as seen in Fig. 1, said cross-pieces being attached to the rails of the track in any desired and well-known manner. To the top or upper end of the track *A* is attached the hinged or jointed extension *B*, which is of the same width as the track *A*, and is constructed substantially in the same manner, and is designed to lie on the ground or pavement contiguous to the hatchway of a cellar.

To the hinged or jointed extension *B* is attached the extension *C*, said extension being substantially of the form shown in the drawings. To the upper ends of the track *A* are attached the ratchet-arms *D*, similar arms being attached to the ends of the extension *B*, as seen in Fig. 1, these arms being for the purpose of forming a hinge or joint by means of the rod *E*, said rod being provided upon one end with the head *a*, as seen in Fig. 2. The opposite end of the rod *E* is provided with a screw-thread, which receives the lever *b*. On the rod *E* is located the hollow pipe *F*, which is for the purpose of pressing against the arms *D* when the lever *b* is turned against the arms *D*, thus forming a rigid connection at any desired angle by means of the ratchet-arms *D*.

The joint or hinge arms *G* are attached to the extensions *B* and *C*, substantially as shown in the drawings, and are substantially of the form shown in Fig. 4. These arms *G* are provided with the shoulders *d*, which are for the purpose of preventing the extension *C* from coming too far forward while raising or lowering a barrel or other article, and at the same time permitting said extension to drop, as seen in Fig. 6.

The truck or carriage *H* is substantially of the form shown in the drawings, and is provided with the wheels *H'*, which may be of the form shown in the drawings, or may be of any other desired form, said wheels being provided with suitable flanges to hold the truck on the track.

The truck or carriage *H* is provided with the pins *h*, (best seen in Fig. 1,) and are for the purpose of attaching the handle and skid *I* to the truck, as seen in Fig. 7. Bars may be used in place of the pins *h*, if desired. The handle and skid *I* is substantially of the form shown in Fig. 5, and is provided with the recessed ends *J*, to engage the pins *h*, thus forming either a handle or skid to the truck *H*, so that the truck may be moved about a cellar or other place when said truck is detached from the track, and at the same time can be used as a skid, as seen in Fig. 7. To the free end of the extension *C* is attached the windlass *K*, which may be of the form shown in Fig. 1. To the windlass *K* is rigidly attached the ratchet-

wheel K', which engages the dog K² in the ordinary manner. To the extension C is attached the brake-lever L, which is for the purpose of retarding the motion as articles are being lowered, and is operated in the ordinary manner. The rope or cord M is attached to the rear axle of the truck or carriage H, and passes over the forward axle of said truck or carriage, so as to prevent the truck from tipping backward as it is being elevated or lowered. The opposite end of the rope or cord M is attached to the windlass K, as seen in Fig. 1. On the hollow pipe F is loosely attached the spool N, so that the rope or cord M will easily pass said pipe F.

In order to dump a barrel at the bottom a stick is placed a short distance from the lower end of the track A, as seen in Fig. 8, so that as the truck H descends the rear wheels will strike the stick and throw the truck in the position shown in said Fig. 8.

When it is desired to load heavy articles into a wagon, the joint or hinge at x is made rigid, and the extension C placed in the position shown in Fig. 6, and the forward end of the extension placed on the wagon, when the rope or cord O is attached to the windlass O' and passes over the spool O², as seen in Fig. 1, and attached to the rear axle of the truck or carriage H, and the crank P attached to the windlass O'. The crank P is provided with the spring-catch P', so that said crank can be easily detached from one windlass and easily attached to the other.

In case it is desired to use a horizontal extension at the bottom or lower end of the track A it may be attached, as at x, as seen in Fig. 1. The joint or hinge at z, Fig. 1, is formed by means of a rod similar to that used at x. The wheels H' are provided with the flat faces R, so that the truck or carriage may be moved about a cellar or other place after it has been detached from the track A.

Having now fully described my invention, what I claim as new, and desire to secure by Letters Patent, is—

1. In a barrel - elevator, the combination, with the main track-section A for a wheeled truck, of a secondary track-section, B, hinged to one end of the main track-sections, an extension track-section, C, hinged to one end of the secondary track-sections, a winding-drum or windlass mounted in the upper end of the

extension track-section, and a cable for connecting the drum with a wheeled truck adapted to travel on the main and secondary track-sections, substantially as described. 55

2. The combination of the main track-section A for a wheeled truck, the secondary track-section B, hinged to one end of the main track-sections, an extension track-section, C, hinged to the secondary track-sections, spools N and O² at the ends of the secondary track-section, a windlass, O', mounted in the main track-section, and a cable, O, substantially as 65 described.

3. The hollow pipe F, located on the rod E, in combination with the ratchet-arms D and the track A, substantially as and for the purpose specified. 70

4. The joint or hinge arms G, provided with the shoulders d, in combination with the extensions B and C, substantially as and for the purpose specified.

5. The handle and skid I, provided with 75 the recessed ends J, in combination with the truck or carriage H, substantially as and for the purpose specified.

6. The extension C, provided with the windlass K, said windlass being provided with the 80 ratchet-wheel K', which engages the dog K², substantially as and for the purpose specified.

7. The ratchet-arms D, located on the track A, and the extension B, substantially as and for the purpose specified. 85

8. The crank P, provided with the spring-catch P', in combination with the windlasses K and O', substantially as and for the purpose specified.

9. The windlasses K and O', having attached 90 thereto the ropes or cords M and O, in combination with the truck or carriage H, substantially as shown and described.

10. The truck or carriage H, provided with the flanged wheels H', and having the elevating rope or cord attached to the rear axle of said truck or carriage, and said elevating rope or cord passing over the forward axle, substantially as and for the purpose specified. 95

In testimony that I claim the above I have 100 hereunto subscribed my name in the presence of two witnesses.

LEVI PENTZ.
